 No Drawing. Filed Nov. 7, 1963, Ser. No. 322,014
 8 Claims. (Cl. 260—534)

This invention relates to an improved process for preparing penicillamine and, more particularly, to an improved process for preparing penicillamine by degradation of a penicillin, such as penicillin G.

Prior to this invention it was known that penicillins could be converted to penicillamine by a series of steps involving alkaline hydrolysis of the penicillin to the corresponding penicilloic acid, decarboxylation of the penicilloic acid to penilloic acid, treatment of the penilloic acid with a mercuric salt, such as mercuric chloride, to yield a penicillamine-mercuric salt complex, isolation of the complex, and conversion of the complex to penicillamine by treatment with hydrogen sulfide. Moreover, it was known that the penicillamine thus formed could be further purified and recovered in higher yield if it was first converted to its isopropylidene derivative, by treatment with acetone, and then reconverted to a salt of penicillamine by reacting the isopropylidene derivative with an acid, such as hydrochloric acid (see British Specification No. 854,339).

Unfortunately, when such process is carried out, in addition to the desired intermediates and end products, various undesired by-products are also found, which interfere with the desired process and the recovery of the desired products. The main interfering by-product is a penilloaldehyde (e.g., benzyl penilloaldehyde if penicillin G is used as the starting material), which, if not removed prior to the conversion of the mercuric complex, greatly reduces the recoverable yield of penicillamine. In fact, if the reactions are carried out in an aqueous alcoholic menstruum the yield of desired product, if the penilloaldehyde is not removed, is reduced to substantially zero.

It is an object of this invention, therefore, to provide an improved method for preparing penicillamine from penicillins.

It is another object of this invention to provide in the process for preparing penicillamine from penicillins for the removal of penilloaldehydes prior to the conversion of the penicillaminemercuric salt complex to penicillamine.

These objects are accomplished by the process of this invention which in its broadest sense entails the step of removing the penilloaldehyde formed in the conversion of a penicillin to penicillamine prior to the conversion of a solution of the penicillamine-mercuric salt complex formed therein to penicillamine. This removal may be achieved by solvent extraction, but preferably is accomplished by converting the penilloaldehyde to an insoluble derivative by treatment with a carbonyl reagent. To accomplish this the penicillamine-mercuric salt complex is dissolved, if not already in solution, in an aqueous or aqueous alcoholic solution, the desired carbonyl reagent is added, and the precipitated derivative is removed as by filtration or centrifugation. To assure that only the penilloaldehyde derivative is precipitated, the reaction is preferably carried out under acidic conditions. The filtrate, freed from the undesired penilloaldehyde, is then further treated in the manner known to the art to ultimately yield D-penicillamine or a salt thereof.

Although any penicillin may be used as the starting material and such penicillins as 2-pentenyl-penicillin and p-hydroxybenzyl penicillin are operative, because of its availability and comparatively low cost, the preferred

penicillin is penicillin G. The penicillin, preferably in the form of a water-soluble salt, such as an alkali metal salt (e.g., potassium benzylpenicillin) is dissolved in water. A base, such as an alkali metal hydroxide (e.g., sodium hydroxide), is then added to hydrolyze the penicillin to the corresponding penicilloic acid.

The penicilloic acid is then decarboxylated by treatment with a concentrated strong acid, such as a concentrated mineral acid (e.g., hydrochloric acid) to yield the corresponding penilloic acid. The penilloic acid is then treated with a mercuric salt, such as a mercuric halide (e.g., mercuric chloride) to yield the mercuric salt complex of penicillamine. To assure that the complex remains in solution, sufficient acid is added to yield a final pH of about 1.3 to about 1.8. The resulting solution is then filtered or centrifuged to remove insoluble impurities.

In accordance with the improvement of this invention, the resulting solution of the mercuric salt complex of penicillamine is then treated to remove penilloaldehyde. Although this removal may be done by solvent extraction, as by treating with chloroform, ethyl acetate or methylene chloride, in accordance with the preferred method of this invention, the removal is accomplished by treating the solution with a carbonyl reagent to yield an insoluble derivative of the penilloaldehyde. Although any carbonyl reagent that forms an insoluble derivative with penilloaldehyde may be used, the preferred reagents include hydroxylamine, semicarmazine, thiosemicarbazide, substituted semicarbazides, substituted benzohydrazides, and optimally hydrazines, such as phenyl hydrazine and substituted phenyl hydrazines, such as nitro, dinitro, halo (e.g., bromo) and dihalo (e.g., dichloro) phenyl hydrazines. To aid in the rate of reaction between the penilloaldehyde and the carbonyl reagent, the solution is preferably heated, optimally to a temperature in the range of about 40° C. to about 60° C. The resulting mixture is then allowed to cool to room temperature and the precipitated derivative of the penilloaldehyde is removed by filtration or centrifugation. In the preferred method of this invention, the mixture is treated with additional acid, optimally about one mole of concentrated mineral acid per mole of penicillin, to assure that no complex is coprecipitated with the penilloaldehyde derivative.

After removal of the interfering penilloaldehyde by-product, the filtrate, containing the mercuric salt complex of penicillamine in solution, is treated with hydrogen sulfide to precipitate the mercury as the insoluble sulfide, the precipitate is removed by filtration or centrifugation, and the resulting solution is mixed with an ester, such as a lower alkyl ester of a lower alkanic acid (e.g., isobutyl acetate, ethyl acetate and isopropyl acetate), or an alcohol, such as a lower alkanol (e.g., isopropyl alcohol and n-propyl alcohol), or a mixture thereof, and refluxed and/or distilled to remove the water. After all the water has been removed, the reaction mixture is cooled and filtered.

The dissolved penicillamine can then be further purified by converting it to the isopropylidene derivative by treatment with acetone and converted to a salt of more purified penicillamine as more fully detailed in Example 1.

The process of this invention, involving the step of removing the penilloaldehyde from the solution of mercuric salt complex of penicillamine prior to treatment with hydrogen sulfide, is more practical for the commercial production of penicillamine than is any previously known method including the one described in British specification 854,339 for a number of reasons. In the first place, the yield of recoverable penicillamine is higher. In addition, the volumes of solvents used are smaller, the penilloic acid is not isolated, less mercuric salt is used, the mercuric salt complex is not isolated, and there is no need to remove all solvent by concentration to dryness, a step

which is impractical on a commercial scale operation. All of these advantages either reduce the cost of the operation and/or increase the yield or purity of the recoverable penicillamine.

The following examples illustrate the invention (all temperatures being in centigrade):

EXAMPLE 1
Penicillamine Hydrochloride

(a) *Preparation of mercuric chloride complex of penicillamine.*—To a solution of 372 g. (1 mole) of potassium benzyl-penicillin in 940 ml. of distilled water at room temperature is added a solution of 40 g. (1 mole) of sodium hydroxide in 180 ml. of distilled water over a period of one-half hour. The solution is then stirred for two hours at room temperature. While maintaining room temperature, 67 ml. of concentrated hydrochloric acid is added at a slow rate. This solution is then added, over a period of time of one-half hour, to a solution of 271 g. (1 mole) of $HgCl_2$ in 3.52 l. of distilled water in the presence of 50 g. of Hyflo and 5 ml. of octyl alcohol. After one hour of agitation, the resulting mixture is treated with 185 ml. of concentrated hydrochloric acid and filtered.

(b) *Removal of benzylpenilloaldehyde.*—To the filtrate obtained in step (a), warmed to 50° is slowly added 108 g. (1 mole) of phenyl hydrazine. The mixture is cooled to room temperature and 84 ml. of concentrated hydrochloric acid are added. The mixture is agitated briefly and the precipitated benzylpenilloaldehyde phenylhydrazone is filtered off.

(c) *Preparation of isopropylidene penicillamine hydrochloride.*—To the filtrate obtained in step (b) is added at 20–25° a total of 85 g. of hydrogen sulfide. The precipitated HgS is filtered off and the filtrate is concentrated under reduced pressure to a volume of 200–500 ml. Following a polish filtration, the product-rich concentrate is mixed with 1.5 l. of isobutyl acetate. The mixture is refluxed at about 40° under reduced pressure in equipment fitted with a water separation device. When no further water separates, the batch is cooled to 30° and filtered. The reactor is washed with 1 l. of acetone, which is used also to wash the cake. The cake is further washed with 200 ml. of acetone. The acetone washes are added to the isobutyl acetate filtrate and the mixture is refluxed for 20–30 minutes. After a holding period of one hour at 5°, the crystals of isopropylidene penicillamine hydrochloride are filtered and washed with 200 ml. of acetone. On drying for twelve hours at 25° this product, containing one mole of water, weighs about 178 g. (73%).

(d) *Preparation of penicillamine hydrochloride.*—The 178 g. of isopropylidene penicillamine hydrochloride obtained in step (c) is dissolved in 350 ml. of distilled water. The solution is heated at 90–95° for one to one and one-half hours, removing acetone by distillation through an efficient column. There is then added 2.6 l. of isobutyl acetate. The mixture is refluxed at a temperature of about 40° under reduced pressure in equipment fitted with a water separation device. When no further water separates, the pressure is adjusted so that the mixture distills at a vapor temperature of 83–88°. A total of 650 ml. of distillate is collected. The batch is allowed to cool to 50° and then filtered. The crystals are washed with isobutyl acetate and then dried at 35° for 24 hours. The virtually anhydrous penicillamine hydrochloride obtained weighs about 128 g. (69% from potassium benzyl-penicillin).

Following the procedure of Example 1 but substituting ethyl acetate, isopropyl acetate, isopropanol or n-propanol for the isobutyl acetate in steps (c) and (d), results in substantially the same yield of penicillamine hydrochloride.

By way of contrast, if step (b) is omitted from the procedure of Example 1, the yield of penicillamine hydrochloride is reduced to about 30%.

EXAMPLE 2

A filtrate obtained by the procedure of step (a) of Example 1 is added to a hot solution of 198 g. of 2,4-dinitrophenylhydrazine in 20 l. of 95% ethanol and 300 ml. of concentrated hydrochloric acid. On cooling, the precipitated benzylpenilloaldehyde 2,4-dinitrophenyl-hydrazone is filtered off. After distilling off the ethanol, the filtrate is worked up as described in steps (c) and (d) of Example 1 to yield penicillamine hydrochloride in approximately the same overall yield as was obtained in Example 1.

EXAMPLE 3

To a filtrate obtained by the procedure of step (a) of Example 1 is added a solution of 69 g. of hydroxylamine hydrochloride in water. The solution is warmed briefly at 50°. After refrigeration, the precipitated benzylpenilloaldehydeoxime is filtered off. The filtrate is then worked up as described in steps (c) and (d) of Example 1 to yield penicillamine hydrochloride in an overall yield of about 55% to 60%.

EXAMPLE 4

(a) *Preparation of mercuric chloride complex of penicillamine.*—A mixture of 372 g. (1 mole) of potassium benzylpenicillin, 1.5 l. of isopropanol and 168 ml. of concentrated hydrochloric acid is refluxed for one hour. After cooling to 5°, the precipitated salt is removed by filtration. To the filtrate is added a solution of 271 g. (1 mole) of $HgCl_2$ in 2.7 l. of 50% isopropanol.

(b) *Preparation of penicillamine hydrochloride.*—The clear solution obtained in step (a) is then treated with 2,4-dinitrophenylhydrazine as described in Example 2 and then further worked up as described in Example 2 to yield penicillamine hydrochloride in an overall yield of about 58–61%.

By way of contrast, if the step of adding 2,4-dinitrophenyl-hydrazone is omitted from the procedure of Example 4, the yield of penicillamine hydrochloride is substantially zero.

EXAMPLE 5

Penicillamine

Following the procedure of Example 1 but substituting the following procedure for step (d) yields penicillamine base:

40 g. of isopropylidene penicillamine hydrochloride obtained in step (c) of Example 1 is dissolved in 80 ml. of distilled water. The solution is heated at 90–95° for about 45 minutes, removing the formed acetone by distillation. The solution is polish filtered and diluted with 800 ml. of isopropanol. The mixture is distilled at atmospheric pressure to remove about 500 ml. of solvent, leaving a residual solution of about 380 ml., consisting of approximately 95% isopropanol. The solution is cooled to 50°, blanketed with nitrogen and treated with 6 ml. of distilled triethylamine. A small amount of gelatinous precipitate forms but it is quickly converted to crystals by agitation. A further 17 ml. of triethylamine is added over 20 minutes to complete crystallization of the product. The crystals of D-penicillamine are cooled at 5° for one hour, filtered and washed well with isopropanol and dried for 20 hours at 55° to yield about 23.0 g. of D-penicillamine product.

65 The invention may be variously otherwise embodied within the scope of the appended claims.

What is claimed is:

1. In the process for converting penicillins to penicillamine by hydrolysis of penicillin to penicilloic acid, decarboxylating the penicilloic acid to penilloic acid, treating the penilloic acid with a mercuric salt to yield a solution of penicillamine-mercuric salt complex and a by-product penilloaldehyde, and converting said complex to penicillamine, the improvement which comprises separating the by-product penilloaldehyde from the penicillamine-mercuric salt complex by acidifying said solution to a

pH within the range of about 1.3 to about 1.8 and precipitating the by-product penilloaldehyde from this acidified solution with a reagent selected from the group consisting of hydroxylamine, semicarbazide, thiosemicarbazide, benzohydrazide, phenylhydrazine and substituted phenylhydrazine, wherein the substituent is a member of the group consisting of nitro, dinitro, halo and dihalo.

2. A process in accordance with claim 1 wherein the reagent is phenylhydrazine.

3. A process as in claim 1 wherein the reagent is dinitrophenylhydrazine.

4. A process as in claim 1 wherein the reagent is hydroxylamine.

5. A process for separating a penilloaldehyde from a mixture with a penicillamine-mercuric salt complex which comprises forming an aqueous solution of said penilloaldehyde and penicillamine-mercuric salt complex by acidifying to a pH within the range of about 1.3 to about 1.8 and precipitating the penilloaldehyde from this acidified solution with a reagent selected from the group consisting of hydroxylamine, semicarbazide, thiosemicarbazide, benzohydrazide, phenylhydrazine and substi-

tuted phenylhydrazine, wherein the substituent is a member of the group consisting of nitro, dinitro, halo and dihalo, and removing the precipitate formed.

6. A process as in claim 5 wherein the reagent is phenylhydrazine.

7. A process as in claim 5 wherein the reagent is dinitrophenylhydrazine.

8. A process as in claim 5 wherein the penilloaldehyde is benzylpenilloaldehyde.
